UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

RAILWAY-CAR.

1,171,661.

Specification of Letters Patent.

Patented Feb. 15, 1916.

Application filed December 4, 1914. Serial No. 875,432.

To all whom it may concern:

Be it known that I, THOMAS N. RUSSELL, a citizen of the United States, residing at Chicago, in the county of Cook and State of Illinois, have invented certain new and useful Improvements in Railway-Cars, of which the following is a specification, reference being had to the accompanying drawings.

10 My invention relates to railway cars, and it has for its object the provision of a new and improved form of car end construction.

15 It is common in railway cars to brace the upper framework of the car very strongly against movement longitudinally of the car relative to the lower framework thereof.

It is the object of my invention to provide a car end which may be connected at its ends 20 to the upper and the lower framework, respectively, the form being such that there may be a maximum of strength vertically so as to protect against the closure members being bowed outward along a horizontal intermediate line. As is well known, in the use 25 of a car carrying a load, enormous stresses are brought to bear upon the ends of the cars, and it is accordingly necessary that very great care be given to the matter of 30 providing a strong well-braced construction of closure members so as to insure the car being maintained in first-class condition under ordinary conditions of use.

The objects of my invention have been attained by the use of a construction such as 35 that shown in the drawings involving the use of steel plate closure members having pressed therein in vertical position a plurality of strengthening ribs or corrugations, the upper edge of the closure plate, whether of 40 one or more sections, being very securely fixed to an end plate which is, in turn, strongly made and securely braced.

It is another object of my invention to 45 provide a car end of the type described which shall be given the maximum strength at about a point where the maximum pressure is brought to bear against the end.

It is another object of my invention to 50 provide a new and improved juncture be-

tween the several sections of a multiple-part end-closure plate.

It is another object of my invention to improve the form and construction of cars in sundry details hereinafter pointed out.

In the drawings,—Figure 1 is a perspective view of the end of a car embodying one form of my improved construction, the roof being removed therefrom the better to illustrate the construction and arrangement; 60 Figs. 1^a, 1^b and 1^c are enlarged details, being fragmentary sectional views taken on correspondingly-indicated lines in Fig. 1; Fig. 2 is a sectional view, being taken substantially on line 2—2 of Fig. 1; Fig. 3 is an enlarged detail of the outer end of the end plate; 65 Fig. 4 is a sectional view, being taken substantially on line 4—4 of Fig. 1; Fig. 5 is a vertical section through a modified form of end-closure plate; Fig. 6 is a fragmentary 70 view showing a modified form of end plate with the end-closure plate secured thereto; Fig. 7 is a fragmentary view showing still another form of end plate, and showing a modified form of end-closure plate connected 75 therewith; Fig. 8 is an enlarged detail illustrating one of the outer ends of the end plate shown in Fig. 7.

Referring to Figs. 1 to 4, in which corresponding parts are designated by the same reference characters,—10 indicates the end sill and 11 the side sill of a car embodying one form of my improved construction. As shown in Fig. 1, a belt rail 12 is provided approximately midway between the 85 side sill 11 and the side plate 13, the side plates 13 at opposite sides of the car being secured together by an end plate 14. Gussets 15 are secured to the side plates 13 a short distance from the end plate 14, 90 bracing members 16 being employed for connecting the gussets with the end plate, whereby the end plate 14 is very strongly reinforced and braced relative to the side plates 13. Secured upon the outer faces 95 of the side sill 11, the belt rail 12 and the side plate 13 at each side of the car are the vertically-extending side sheathing boards 17 secured in proper position upon the side sills 11, and suitably supported. 100

therefrom, there are decking boards 18 of any suitable type. The end plate 14 comprises a vertically-extending portion 19 and two inclined portions 20 formed integrally with the vertically-extending portion 19, the end plate being preferably pressed out of sheet steel. At the lower edge of the end plate 14 there is provided a flange 21 offset outwardly relative to the portion 19 of the end plate. As best shown in Fig. 3, the offset of the flange 21 is faded out at the ends of the plate, and the ends of the portion 19 and of the flange 21 are turned at right angles so as to stand outside of the sheathing 17. The ends of the inclined portions 20 of the end plate are turned downward about the side plates 13 inside of the sheathing 17, as will be appreciated from an inspection of Figs. 1 and 3.

My end-closure means comprises, in the construction shown, two sheet metal sections or members 22-23 arranged in vertical position side by side. As is shown in Fig. 2, the lower edges of the sections 22-23 are turned at right angles to provide flanges 24, which are secured by means of bolts 25 to the end sills 10. At their upper ends the plates 22-23 underlie the flange 21, with their upper edges abutting the offset portion of the said flange, being secured in such position by means of a plurality of rivets 26. At their vertical outer edges the plates 22-23 are turned at right angles about the side sheathing 17, being secured in position by a plurality of bolts 27. Tie-plates 28-29 are securely riveted to the flanged outer edges of the plates 22-23 opposite the belt rail 12 and the side sill 11, respectively, such tie-plates being secured in position by means of bolts 30, the plate 29 being extended diagonally downward so as to have a proper bearing upon the side sill.

As is best shown in Fig. 4, at their meeting edges the sections 22-23 of the end-closure plate are provided with flanges 31-32, respectively, by which such sections are adapted to be secured together by rivets 33, strips 34 of felt, tar paper, or other comparatively firm yielding material, being interposed between the flanges 31-32 for making a weather-tight joint between such sections. As is best shown in Fig. 1, the flange 21 has pressed in it a groove 21^a to receive the upper ends of the flanges 31-32, which are tapered off to enter such groove.

For the purpose of giving the end-closure plate the maximum of strength vertically so as to prevent the bulging of the end-closure member relative to the end plate and the end sill, which are by far the most strongly braced parts at the end of the car, I have provided strengthening ribs

or corrugations 35, pressed in such plate, 65 extending vertically directly between the end plate and the end sill. In this way, by reason of the end-closure plate being secured at its edges to the most strongly braced parts of the end construction and 70 being provided with strengthening ribs leading from one to the other of said strongly braced parts, I have secured a very strong arrangement and construction, 75 adapted to resist successfully the heavy 80 stresses brought to bear in normal use upon the end-closure member.

Referring to the construction in Fig. 5, corresponding parts are designated by the same reference characters, but with the addition of an exponent "a." In this construction, a closure plate 36 is shown corresponding to that shown in Fig. 1, but having a modified form of strengthening rib 37 pressed therein. As is well understood in the car art, the maximum pressure upon a car end, when the car is loaded with grain, or other easily shiftable material, up to the normal height therein, is along a line from two feet to two and one-half feet above the 90 floor. I have accordingly provided the rib 37 of varying depth so as to secure a maximum of strength at the point where the maximum pressure will be brought to bear.

In Fig. 6, which illustrates a modification 95 of the form shown in Fig. 1, the parts are indicated by the same reference characters, but with the addition of an exponent "b." The end plate of Fig. 6 differs from the end plate of Fig. 1 in that the vertically-extending 100 part 19^b of the end plate of Fig. 6 is not provided with an offset flange at its lower edge, but is brought straight down to overlap the upper edge of the sections 22^b-23^b, the end plate 14 being spaced a slight distance farther from the middle of the car for the accomplishment of this end, and the flanges 31^b-32^b being cut away at their upper ends 105 even with the lower edge of the portion 19^b of the end plate.

In Figs. 7 and 8 a slightly different form 110 of end plate is shown in position upon a car. In these figures, parts which correspond to the parts of Figs. 1 to 4 are indicated by the same reference characters, but 115 with the addition of the exponent "c." In the construction shown in said Figs. 7 and 8 the end plate is formed out of a heavy angle-iron instead of being formed of a straight steel plate. The result is that the laterally-inclined part 20^c of the end plate is of uniform width throughout its length. The vertically-extending part of the end plate 14^c therefore comprises two inclined bars 38 in lieu of the plate 19 of the construction first 120 described. The end-closure plates 22^c-23^c have their corrugations 35^c extended upward 125 into close proximity to the bars 38, the re-

sult being that the corrugations vary in length from the sides toward the middle.

That which I claim as my invention, and desire to secure by Letters Patent, is,—

1. In a railway car, the combination of a sheet-metal end plate, two sheet-metal end-closure plates arranged side by side and connected at their upper edges to said end plate, said end-closure plates having their adjacent edges turned at an angle to form attaching flanges, a compressible weather-strip interposed between said flanges, means for connecting said flanges firmly together, and inclosing means projecting from the upper edge of the end plate about the upper ends of said flanges.

2. In a railway car, the combination of a sheet-metal end plate, two sheet-metal end-closure plates arranged side by side below said end plate, an offset flange formed on the lower edge of said end plate overlapping said end-closure plates, means for securing said flange to said end-closure plates, flanges formed at the adjacent edge of said end-closure plates, a compressible weather-strip interposed between said last-named flanges, and means for connecting said last-named flanges firmly together, the flange extending across the lower edge of the end plate being pressed outward at the juncture of said two end-closure plates for inclosing the upper ends of the two connected flanges.

3. In a railway car, the combination of a sheet-metal end plate comprising a vertically-extending portion having an offset flange at its lower edge, and two sheet-metal end-closure plates arranged side by side below said end plate with said flange overlapping their upper edges and firmly connected thereto, the ends of the vertically-extending portion of the end plate being turned at an angle to extend along the outer face of the side sheathing, the offset at the lower edge of the end plate being faded out at the turned ends thereof.

4. In a railway car, the combination of an end sill, an end-closure plate secured at its lower end to said end sill and having a plurality of strengthening ribs pressed therein extending upward in vertical position from said end sill to substantially the upper end of said plate and spaced at intervals between the side edges thereof, and an end plate structure extending downward on the outer face of said end-closure plate, said end plate structure comprising bracing means for strengthening it against bowing outward at an intermediate point whereby the end plate and the end-closure plate mutually reinforce each other against strain longitudinally of the car.

5. In a railway car, the combination of a sheet-metal end plate comprising a vertically-extending portion, a sheet-metal end-

closure plate secured at its upper end to said end plate, a tie-plate secured to said end-closure plate at its side edge and extending along the side of the car, means for securing said tie-plate to the belt rail of the car, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.

6. In a railway car, the combination of a sheet-metal end plate comprising a vertically-extending portion, a sheet-metal end-closure plate secured at its upper end to said end plate, a flange on the side edge of the end-closure plate extending about the side sheathing and firmly secured thereto, a tie-plate secured to said flange and extending along the side of the car, means for securing said tie-plate to the belt rail of the car, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.

7. In a railway car, the combination of a sheet-metal end plate comprising a vertically-extending portion, a sheet-metal end-closure plate secured at its upper end to said end plate, a tie-plate secured to said end-closure plate at its lower side corner and extending diagonally downward along the side of the car, means for securing said tie-plate to the side sill of the car, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.

8. In a railway car, the combination of a sheet-metal end plate comprising a vertically-extending portion, a sheet-metal end-closure plate secured at its upper end to said end plate, a flange on the side edge of the end-closure plate extending about the side sheathing and firmly secured thereto, a tie-plate secured to said flange at its lower end and extending diagonally downward along the side of the car, means for securing said tie-plate to the side sill of the car, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.

9. In a railway car, the combination of a sheet-metal end plate comprising a vertically-extending portion and two portions conforming to the slope of the roof of the car, a sheet-metal end-closure plate extending up inside of an offset flange formed on the lower edge of the vertically-extending portion of the end plate, means for securing said flange to said end-closure plate, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.
10. In a railway car, the combination of a sheet-metal end plate comprising a vertically-extending portion and two portions conforming to the slope of the roof of the car, means for bracing said end plate against yielding relative to the car longitudinally thereof, a sheet-metal end-closure plate extending up inside of an offset flange formed on the lower edge of the vertically-extending portion of the end plate, means for securing said flange to said end-closure plate, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.
11. In a railway car, the combination of a sheet-metal end plate comprising a vertically-extending portion and two portions conforming to the slope of the roof of the car, a sheet-metal end-closure plate extending up inside of an offset flange formed on the lower edge of the vertically-extending portion of the end plate, means for securing said flange to said end-closure plate, the ends of the vertically-extending portion of said end plate being turned to extend along the sides of the car and being secured firmly thereto, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.
12. In a railway car, the combination of a sheet-metal end plate comprising a vertically-extending portion and two portions conforming to the slope of the roof of the car, a sheet-metal end-closure plate extending up inside of the vertically-extending portion of the end plate, means for securing the upper edge of the end-closure plate to the vertically-extending portion of the end
- plate, and means for securing the lower end of said end-closure plate to the end sill of the car, said end-closure plate being provided with vertically-extending strengthening ribs adapted to strengthen said end-closure plate against being bowed outward relative to said end sill and said end plate.
13. In a railway car, the combination of a sheet-metal end plate comprising a vertically-extending portion and two portions conforming to the slope of the roof of the car, a sheet-metal end-closure plate extending up inside of the vertically-extending portion of the end plate, means for securing the upper edge of the end-closure plate to the vertically-extending portion of the end plate, and a flange on the lower end of said end-closure plate secured to the upper face of the end sill of the car, said end-closure plate being provided with vertically-extending strengthening ribs adapted to strengthen said end-closure plate against being bowed outward relative to said end sill and said end plate.
14. In a railway car, the combination of a sheet-metal end plate comprising a vertically-extending portion and two portions conforming to the slope of the roof of the car, a sheet-metal end-closure plate extending up inside of an offset flange formed on the lower edge of the vertically-extending portion of the end plate, means for securing said flange to said end-closure plate, and means for securing the lower end of said end-closure plate to the end sill of the car, said end-closure plate being provided with vertically-extending strengthening ribs adapted to strengthen said end-closure plate against being bowed outward relative to said end sill and said end plate.
15. In a railway car, the combination of an end plate, an end sill, and a sheet metal end-closure plate extending from said end plate to said end sill and secured at its ends to said parts respectively, said end-closure plate having pressed in vertical position therein a plurality of strengthening ribs spaced at intervals between its side edges, each of said strengthening ribs being of varying depth increasing toward an intermediate point.
16. An end closure for a railway car comprising a plurality of sheets of metal arranged side by side and having their adjacent edges secured together, means for securing the upper ends of said sheets to the end plate of the car, and means for securing the lower ends of the sheets to the end sill of the car, said sheets being provided with vertically-extending strengthening ribs pressed therein substantially from the end plate to the end sill, said ribs being of increasing depth toward an intermediate point.

17. An end closure for a railway car, comprising two end closure plates secured to each other side by side at the end of the car and secured at their upper ends to the end 5 plate of the car and at their lower ends to the end sill of the car, each of said end closure plates being provided with a plurality of vertically-extending strengthening ribs pressed therein substantially from end to

end of the plate, each of said ribs being of 10 varying depth decreasing in both directions from a point approximately two feet above the deck of the car.
